STORING AND TREATING STRUCTURE FOR
WELDING ELECTRODESGeorge M. Beimer, Rutherford, N. J., assignor to
Couse Laboratories, Newark, N. J., a corpora-
tion of New Jersey

Application November 24, 1943, Serial No. 511,636

2 Claims. (Cl. 34—211)

This invention relates to means for storing and treating welding electrodes.

In electric arc-welding, it is now the standard practice to use coated or covered electrodes, the coatings serving several functions which need not be gone into in this application. However, these coatings will take up moisture which I have found to interfere with the proper welding characteristics that the electrodes should have when the coating is dry. This moisture may be taken up while the electrodes are in storage, or they may be subjected to moisture, especially in open field work particularly in army service.

It is therefore the principal object of my invention to provide means for storing and treating these electrodes.

At the same time it is an ancillary object of my invention to provide means for storing non-coated electrodes which are usually used for gas welding.

A further object is to provide a single structure which will store or handle both types of electrodes.

My invention will be readily appreciated by reference to the annexed drawings, wherein:

Figure 1 is a perspective view of the combination structure to serve both types of electrodes.

Figure 2 is a section on the line 2—2 of Figure 1.

Figure 3 is a section on the line 3—3 of Figure 1.

Figure 4 is a fragmentary view of a part of the front of the structure shown in Figure 1, showing the sealing of the cabinet when the door is closed.

Figure 5 is a section somewhat similar to Figure 3, but through the heating chamber, showing one type of baffle plate which may be used.

Figure 6 is a view similar to Figure 4 but showing a modified form of baffle plate in the heating chamber.

Figure 7 is a fragmentary perspective view of a compartment separator.

Figure 8 is a further modified form of construction showing the heating chamber surrounding the electrode compartments.

In the drawings, 1 is a main cabinet for carrying covered arc-welding electrodes, while 2 is an auxiliary cabinet preferably permanently fastened as by welding to the main cabinet 1. The cabinet 1 is divided into a plurality of compartments by a series of shelves 3 which may be flat metal plates having ventilating holes 4 therein, or the shelves may be of the screen type 5 such as shown in Figure 7.

As shown in Figures 1 and 2, there is positioned, preferably centrally of the main cabinet 1, a heat-

ing chamber 6, the bottom of which is adapted to be connected by a pipe 7 to a source of heat such as the exhaust of the engine that propels the vehicle which, for one type of army use, is of a nature similar to Couse Design Patent D-109-942, issued May 31, 1938, which illustrates what is known in the trade as a traveling machine or repair shop. When the structure is used in a vehicle of this type, it is preferably fastened as by welding directly to some part of the body structure 8 so that it will not be tipped over by the rough going which is encountered many times by this type of vehicle or by army trucks.

The upper end of the chamber 6 is provided with an outlet 9. It is to be understood that the chamber 6 is preferably completely sealed from the two divisions of the cabinet on either side of it, and each of these divisions is provided with one or more breathers 10 to allow the heated vapors coming from the contents of the compartments forming the divisions to pass out of the cabinet.

As shown in Figure 1, the front of the cabinet is provided with a door 11 which is hinged at 12 and held in place by fasteners 13. The door 11 is preferably provided with a ventilating chamber 14 which is adapted to take in dry air, preferably from the bottom, which air passes through the holes 15 into the compartments, the shelves of which are welded to the side and back walls of the cabinet as well as to the heating chamber 6.

In Figure 1 the box 16 of covered electrodes is shown in position in one of the compartments, the cover 17 being in place, which would be the position for storing the electrodes to keep them continuously dry. However, if the electrodes are damp and are to be immediately dried out, then of course the cover 17 is removed.

The auxiliary cabinet 2 is provided with a hinged door 18 and fasteners 19. This cabinet is adapted to carry uncovered electrodes 19 used for gas welding, and since they are uncovered there is no necessity for drying them out.

In Figure 5 the compartments 20 are provided with individual doors 21. These doors may carry labels designating the type or size of electrodes to be found in the various compartments. For that matter, the compartments where a single door is used, as in Figure 1, may be interiorly labeled so that when the door is opened the welder may see the proper designation of the electrodes he desires to use.

In Figure 5, transverse holes 22 are used to assist in ventilating the electrode compartments; that is, they connect the compartments on one

side of the heating chamber with the compartments on the other side, and they are located closely to the curved rear walls of the heating chamber against which the hot gases are directed by the baffles.

Preferably, a sealing gasket 23 is used for the main door 11 as shown in Figure 4.

In Figure 8, the compartments 28 are spaced from the side walls of the cabinet where the heating chamber 6 is of a form which passes around at least two sides of the compartments.

While I have shown a storage and treating structure especially adapted for use with engine-propelled vehicle repair shops, the cabinets may be utilized in other places where there is a source of heat for passing through the heating chamber. Hence, I do not want to be unduly limited in the interpretation of the appended claims.

What I claim is:

1. Conditioning means for covered arc-welding electrodes used in field service on an engine propelled vehicle repair shop, said means comprising a cabinet having two vertically spaced rows of shelf type compartments to receive electrodes, the shelves having ventilation openings therein, each compartment having its own door, at least the top and bottom doors provided with air chambers to pass air into the compartments through the openings in said shelves, a heat transferring chamber centrally located between 30

5 said rows of compartments and extending straight across the cabinet with its rear wall terminating in close proximity to the rear wall of the cabinet thereby forming a small space chamber thereat, means for passing heat coming from said engine to and from said heating chamber and means for ventilating the compartments, the ventilation being assisted by transverse passages connecting the compartments on one side of the heating chamber with the corresponding compartments on the other side by way of said space chamber.

10 2. A structure for carrying and conditioning covered arc-welding electrodes in an engine-propelled vehicle repair shop comprising a steel cabinet adapted to be fastened to the framework of the vehicle, the cabinet having a centrally located closed heating chamber extending clear across one dimension of the cabinet and welded to at least one of its walls, compartments having 15 perforated shelves fastened to the side walls of the cabinet and to the heating chamber, a door for said compartments, said door having means defining a ventilating chamber open at one end, 20 said door having openings therein for admitting air from said ventilating chamber to said compartments, means for circulating engine exhaust gases through said heating chamber, and means 25 for venting said compartments.

GEORGE M. BEIMER.
